UNITED STATES PATENT OFFICE.

WILLIAM P. COTTRELL, OF LOS ANGELES, CALIFORNIA.

PANNING-MOVEMENT.

1,363,495.

Specification of Letters Patent. Patented Dec. 28, 1920.

Application filed February 2, 1920. Serial No. 355,705.

To all whom it may concern:

Be it known that I, WILLIAM P. COTTRELL, a citizen of the United States, residing at Los Angeles, in the county of Los Angeles and State of California, have invented new and useful Improvements in Panning-Movements, of which the following is a specification.

This invention relates to a mechanical movement especially adapted for riffle concentrating tables, which separate minerals from their gangue by stratification induced by agitation moving the ore longitudinally of the riffles.

It is an object of this invention to provide a movement adapted for a riffled table, whereby after each jolt of the table, the latter is given a downward movement thereby relieving the pressure of the particles of ore upon the table's surface. It is another object of this invention to provide means whereby the drop movement of the table may be adjusted. It is found that stratification of the ore is much more efficient when the ore is tossed from the table or the table moved from beneath the ore in its agitation and movement longitudinally of the table. The amount of the movement for efficient operation is dependent upon the grade and quality of the ore and upon the depth of the riffles. For this reason it is desirable that the drop movement be made adjustable to accommodate the machine to ore of various characteristics and to the depth of the riffles.

These objects will be more fully understood, as will also other objects and corresponding accomplishments of my invention from the following detailed description of a preferred embodiment thereof. For the purpose of this description, reference is had to the accompanying drawing, in which:

Figure 1 is a side elevation of my improved movement applied to a table, the details of the table not being shown; Fig. 2 is an enlarged detail view of the bumper and buffer construction; and Fig. 3 is a section taken on the line 3-3 of Fig. 2.

The bed of a concentrating table is indicated by 4. This table is of the type which is reciprocated and jolted at each vibration. A base 5 is provided with cross beams 6. Mounted upon two of the cross beams is a bearing block indicated by 7 and 7' in registry with the side of the table. Pivots mounted in the bearing blocks are support-

ing links 8 and 8'. The upper ends of the supporting links are pivotally secured to bearing blocks 9 and 9' mounted upon the side of the table bed. The construction just described is duplicated upon the opposite side of the table. Links 8 and 8' are inclined to the vertical, and, in the construction shown link 8 has a greater angle of inclination than 8'. Extending transversely across the table bed is a bumper beam 10.

Secured to the base is a channel bar 11, which has a horizontal portion 12. Adjustably mounted in the channel is a buffer 13 having a resilient head 14, preferably of rubber. The upper face of the buffer is inclined so as to make it wedge shaped. Embracing the buffer and the channel bar is a clamp 15. It is obvious that the position of the buffer may be adjusted longitudinally of the channel. The bumper strikes the buffer head at each vibration of the table, and the construction is so arranged that normally the bumper is in contact with the buffer. After adjustment and fixing of the buffer to the channel bar, sliding of the buffer along the channel is prevented by reason of its wedge shape. Extending transversely of the table to the rear of the channel is a cross piece 16 corresponding to a bumper beam 10. Secured to the under face of the beam 16 is an angle 17, and secured to the bumper beam in a corresponding position is an angle 18. Extending between the angles and secured thereto is a rod 19. The rod slidably extends through the legs of the channel 11. Mounted upon rod 19 is a helical compression spring 20. The spring abuts the channel on the inside and a washer 21 held in position by a nut 22 threaded upon the rod. A similar compression spring 23 abuts the channel 11 and a washer 24 is held in position by a nut 25. By adjustment of nuts 22 and 25 the compression of the springs 20 and 23 may be adjusted.

Journaled on the table bed 4 is a shaft 26, and secured to said shaft is a pulley 27. Secured to the pulley is an eccentric 28. This eccentric serves as an overbalance weight to vibrate the table. Journaled on the base is a driving pulley 29, and passed over the pulleys 29 and 27 is a belt 30.

It is obvious that the more the supporting links 8 are inclined to the vertical, the more will be the drop of the table upon each movement thereof in a horizontal direction. By adjusting the position of the buffer 13,

keeping bumper 10 in contact therewith, the drop of the table upon vibration may be adjusted. The larger the riffles, the greater should be the drop. After having made this 5 adjustment, spring 20 is adjusted to hold the table without movement at the selected speed of the pulley 27. Thus, if the table is to be operated at 600 vibrations per minute, the spring 20 should be adjusted so that 10 at this speed there is no vibration of the table. The compression of spring 23 is then adjusted so as to counteract the effect of spring 20 just enough to allow vibration of the table at the selected speed. 15 Upon rotation of shaft 26, the eccentric 28 being overbalanced, causes the table to vibrate. The table is moved to the left end against the action of compression spring 20. The compression spring 20 assists the 20 eccentric in moving the table to the right, whereupon the bumper 10 comes in violent contact with the buffer 13. This gives a jolt to the table and tends to move the ore toward the tail end. Upon the rebound and 25 movement of the table to the left, it drops from beneath the ore, leaving the latter suspended, which act produces a maximum of stratification. The amount of movement along the table is controllable by the amount 30 of drop, so that if sufficient drop is given the table may be slightly tilted longitudinally with its tail end higher than the head end. In this position particles will travel along the table in an up-hill direction. 35 With the links at the head end having the greater inclination, the drop at that end is greater. This is advantageous where the riffles are larger at the head end.

What I claim is:

40 1. A mechanical movement comprising the combination of a reciprocable member having a bumper, a stationary buffer, spring means normally holding said bumper in contact with said buffer, means to support said

member to permit longitudinal vibration 45 and cause up and down movement thereof, and means to reciprocate said member.

2. A mechanical movement comprising the combination of a reciprocable member having a bumper, a stationary buffer, spring 50 means normally holding said bumper in contact with said buffer, means to support said member to permit longitudinal vibration and cause up and down movement, said means being adjustable, and means to reciprocate said member.

3. A mechanical movement comprising the combination of a reciprocable member having a bumper, a stationary buffer, adjustable spring means normally holding said 60 bumper in contact with said buffer, means to support said member to permit longitudinal vibration and cause up and down movement, said means being adjustable, and means to reciprocate said member.

4. A mechanical movement comprising the combination of a reciprocable member having a bumper, a stationary buffer, spring means normally holding said bumper in contact with said buffer, supporting links 70 for said table pivotally mounted so as to be rocked, means to adjust the normal inclination of said links, and means to reciprocate said members.

5. A mechanical movement comprising 75 the combination of a reciprocable member having a bumper, a stationary buffer adjustable longitudinally of said table, spring means normally holding said bumper in contact with said buffer, supporting links 80 for said table pivotally mounted so as to rock, and means to reciprocate said members.

In witness that I claim the foregoing I have hereunto subscribed my name this 23rd 85 day of January, 1920.

WILLIAM P. COTTRELL.
